UNITED STATES PATENT OFFICE.

WILLIAM T. BOOTH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SET.

1,341,007.

Specification of Letters Patent. Patented May 25, 1920.

Application filed June 30, 1917. Serial No. 127,957.

To all whom it may concern:

Be it known that I, WILLIAM T. BOOTH, a citizen of the United States, residing at East Orange, in the county of Essex and State of New Jersey, have invented certain new and useful Improvements in Telephone Sets, of which the following is a full, clear, concise, and exact description.

This invention relates to substation sets for telephone systems, and more particularly to sets designed for vestibule use in systems of the apartment house type.

One object of the invention is to arrange a telephone receiver and a horn therefor in such a way as to protect the transmitter of the set from injury and to this end a receiver is provided with a horn and the two mounted so as to extend over and partially surround the transmitter.

Another object is to provide a wall set of either flush or non-flush type having the receiver arranged within the set in such a way as to provide such a compact arrangement of parts that the outlet box or casing for use therewith is no larger than those required for similar sets having the receiver carried exteriorly. To accomplish this, the receiver is arranged horizontally at the rear of the set and the horn thereof is extended vertically therefrom and bent at its outer end to direct the sound exteriorly of the set.

A further object is to provide a set which may be secured to its front plate or casing as a single unit, and to accomplish this result all the necessary parts of the set, including the receiver and transmitter, are secured on a single mounting plate and this plate secured to the front plate or casing with which it is to be used.

In the drawing Figure 1 is a vertical cross section of a flush type vestibule set, taken on the line 1—1 of Fig. 2, and having the outlet box thereof only partially shown; Fig. 2 is a rear elevation of the set with the outlet box removed; and Fig. 3 is a front elevation thereof on a much smaller scale.

The particular set shown is of the flush type and has a front plate 10 of any suitable material, preferably metal, this plate being of any desired finish. The plate 10 carries a mouthpiece 11 which preferably is either integral therewith or secured thereto in such a way that it is necessary to have access to the rear of the plate before the mouthpiece can be removed. Openings 12 are provided

in the plate 10 above the mouthpiece 11, and an L-shaped horn 13 is located at the rear of the plate and secured to a horizontally arranged receiver 14 to direct the sound therefrom exteriorly of the set. By placing the receiver at the rear of the plate it is not liable to be stolen or tampered with, as is the case where it is located in front thereof. A screen 15 is provided between the plate 10 and the outer end of the horn 13 to cover the openings 12 and to prevent the entrance of foreign matter into the horn 13 and resulting interference with the adjustment of the receiver. The screen 15 is preferably secured directly to the mouth of the horn and carried therewith, but may be secured to the rear of the plate 10 covering the openings 12, if desired. Another opening 16 is provided in the plate 10 below the mouthpiece 11, and a finger key 17 extends therethrough and is pivoted to a bracket 18 carried on a mounting plate 19 which also has an opening through which the key 17 extends. If desired, the portion of the key 17 at the front of the plate 10 may be made sufficiently small to pass through the opening 16 of the front plate 10, thus permitting it to be assembled relative to the front plate without disengagement from its bracket 18. The mounting plate 19 carries all the working parts of the set and is so constructed that all the parts can be arranged thereon and this plate secured as a unit to any one of the number of different front plates, or changed from one front plate to another at any time without mutilation of any of the internal wiring or removal of any of the working parts from the mounting plate.

The receiver 14 is mounted horizontally; an L-shaped lug 20 carried by receiver cap 21 serving to secure the receiver to the mounting plate 19. The receiver casing proper 22 is threaded in this stationary cap 21 and so spaced that it may be readily removed for inspection or adjustment without disturbing other apparatus or interfering with the horn 13, which is carried by the cap 21. The horizontal arrangement of the receiver 14 and the use of an L-shaped horn 13 arranged vertically of the set admits of the apparatus thereof being positioned in an outlet box 23, no larger than those used where the receiver is arranged at the front of the plate 10. This further admits of using a non-flush wall casing of no greater

depth than those used where the receiver is carried exteriorly, in case a non-flush type of wall set is desired, rather than the flush type shown in the drawings.

5 The horn 13 is removably secured to the receiver cap 21 at one end and is provided with an extension 24 on the lower part of the horn at the other end. The lower edge of this part of the horn 13 extends just above 10 the upper end of the mounting plate 19, which admits of the extension 24 extending in front of the upper portion of the mounting plate 19 and provides for the engagement of the extension 24 between the front 15 plate 10 and mounting plate 19 on securing the two plates together. This serves to hold the horn more firmly in position than would be possible by depending only on the engagement of the lower end of the horn with the 20 receiver cap 21.

A transmitter 25 is mounted in a suitable opening in the plate 19 opposite to the mouthpiece 11 and is flanged to engage an annular insulating washer 43 arranged at 25 the rear of and adjacent to the opening in the mounting plate 19, the opening in the washer 43 being slightly less than that in the plate and engaging the side wall of the transmitter 25 to hold it out of contact with 30 the plate 19. Spring clips 26 serve to hold the transmitter firmly in place and are preferably carried on insulating strips 27 secured to the plate 19. The transmitter and the receiver with its horn are relatively positioned so that the horn extends to the rear of and above the transmitter, while the receiver cap extends below the transmitter. This serves to house the transmitter to a great extent and to protect it against injury, 40 especially after assembly of the apparatus on the mounting plate to form a unitary structure, but before the attachment of a front plate thereto. It also provides protection after attachment of the front plate 45 but before installation of the set has been complete, as well as providing a compact structure capable of being used with outlet boxes as small as those heretofore used with flush sets having the receiver located exteriorly.

The bracket 18 and the finger key 17 are secured to the rear of the mounting plate 19 and carry two springs 28 and 29 insulated from each other and normally disengaged 55 at their free ends, but designed, on engagement, to complete the talking circuit of the set in the manner of the usual hookswitch, which it is designed to replace. The front spring 28 is arranged to press the key 17 upwardly to the position shown in Fig. 1, and is insulated from the key by a strip of insulation 30 carried by the spring. On depression of the finger key 17 the springs 28 and 29 are engaged to close the circuit there- 65 through.

The key 17 can, of course, be used as a calling key if desired, but it is desirable if the set be used as a vestibule set that the push buttons usually associated with letter boxes in a vestibule be used for selective signaling as this enables the same kind of set to be used without change in various installations regardless of the particular number of stations of the system. This in turn allows standardization of equipment and materially lessens the different parts necessary to be kept on hand to provide vestibule sets of a particular number of buttons and a correspondingly large number of front plates arranged for different numbers of buttons 80 depending on the number of stations to be connected with in the particular equipment.

A series of binding strips 31, 32, 33, 34 and 35 are mounted upon a block of insulation 36 which is secured to the mounting plate 19 in such a way as to insulate the binding strips from the plate. With all the working parts of the set thus carried on the mounting plate the set can be wired up thereon ready for use. When an order is 90 received all that is necessary is to select the proper front and secure the plate 19 thereto by any suitable means, as, for example, by bolts 37, as shown on the drawing. This can be done whether a flush type wall set 95 or a non-flush type wall set is desired, the only difference being that in the first case the unit is secured to the desired flush plate 10, while in the second case the unit is secured within the desired wooden, or metal, 100 telephone case.

The key 17 may be temporarily removed from its bracket 18 until the plate 19 has been secured in position, whereupon the key can be inserted from the front of the plate 10 and again secured in place; or, if desired, the key 17 may be omitted in the assembly of the unit and after mounting the unit in place a key 17 having a particular finish to harmonize with the particular front plate 110 10, would be secured in place.

A perforated closure 38 is located at the rear of the mouthpiece 11 and positioned over an inturned portion 39 thereof to prevent injury to the transmitter, while a layer 115 of insulation 40 is also provided between the front plate 10 and the perforated protecting plate 41 of the transmitter 25 to insulate the transmitter from the front plate. The insulation 40 has an opening 42 therein 120 in registration with the sound opening in the mouthpiece to provide for the passage of sounds to the transmitter.

It is apparent from the above description that all the necessary parts of the set, such 125 as a switch, contact or binding post strips, transmitter, receiver and horn may be directly assembled on the mounting plate 19 with the wiring of the internal circuit of the set completed, or not, as desired, and 130

kept in this way ready to be positioned directly on any one of the number of plates or casings which might be desired to provide a particular style or finish. The necessary parts thus form a unit ready to be secured to such a front plate or casing of the desired finish, according as to whether a flush or non-flush type of wall set is desired. It also provides for ready repair of damaged sets, as a new unit may be quickly substituted and the damaged unit removed and easily examined, inasmuch as the necessary parts will all be removed by detaching the mounting plate and without affecting the internal wiring of the set.

What is claimed is:

1. A telephone set comprising a front member, a back plate, means to secure said member and plate together, a telephonic member, a horn for said member having one end secured thereto and the other end positioned adjacent said front member, and an extension carried by the end of the horn adjacent said front member extending between said front member and back plate and clamped between them to hold said horn in place.
2. A telephone set comprising an outlet box, a front member adapted to be secured to said outlet box, a back plate removably secured to said front member, a receiver and a transmitter secured to said back plate, and means to permit the free removal of said front member and said back plate from said outlet box as a unit.
3. A telephone set comprising an outlet box, a front plate adapted to be secured to said outlet box, a back plate removably secured to said front plate, telephonic apparatus secured to said back plate, and means to removably secure said front plate to said outlet box for permitting the removal of said telephonic apparatus as a unit.
4. A telephone set comprising an outlet box, a front member adapted to be removably secured to said outlet box, a back plate removably mounted on said front member, and a transmitter, receiver, key and binding posts secured to said back plate and removable as a unit therewith upon the removal of said front member from said outlet box.
5. A telephone set comprising a mounting plate, a transmitter mounted on said plate, a receiver separate from said transmitter, a mounting for said receiver secured to said plate below said transmitter, and a horn carried by said receiver positioned over and partially surrounding said transmitter and coöperating with said receiver to protect the transmitter.
6. A telephone set comprising a front plate having a plurality of openings therein, a back plate removably mounted on said front member, means to removably secure said plates together, a transmitter mounted on said back plate opposite one of said openings in said front plate, a receiver mounted on said back plate, and a horn carried by said receiver and extending therefrom to another of said openings in said front plate; said receiver and horn extending over and partially surrounding said transmitter.
7. A telephone set comprising a vertical mounting plate, a transmitter mounted on said plate, a receiver mounted on said plate below said transmitter and extending horizontally relative to said plate, and a horn carried by said receiver and extending vertically relative to said plate positioned over and partially surrounding said transmitter and coöperating with said receiver to protect the transmitter.
8. A telephone set comprising an outlet box, a cover plate secured to said outlet box and having a mouth-piece formed therein, a mounting plate secured to said cover plate, a transmitter secured to said mounting plate in position to coöperate with said mouth-piece, a receiver mounted in close proximity to said transmitter and secured to said mounting plate, and means to removably secure said cover and mounting plate to said outlet box for permitting the removal of said transmitter and receiver as a unit.

In witness whereof, I hereunto subscribe my name this 26th day of June, A. D. 1917.

WILLIAM T. BOOTH.
